UNITED STATES PATENT OFFICE.

WAYNE E. WEDEMAN, OF BALTIMORE, MARYLAND, ASSIGNOR TO GENERAL ELECTRIC COMPANY, A CORPORATION OF NEW YORK.

ELECTRIC SWITCH.

Application filed August 29, 1921. Serial No. 496,396.

To all whom it may concern:

Be it known that I, WAYNE E. WEDEMAN, a citizen of the United States, residing at Baltimore, county of Baltimore, State of Maryland, have invented certain new and useful Improvements in Electric Switches, of which the following is a specification.

My invention relates to improvements in electric switches and particularly to an improved form of combined clip-block and terminal for high ampere capacity switches and to a method of making such combined clip-block and terminal. An object of my invention is to provide a unitary structure which may be made from standard sizes of copper bars, which shall be simple and durable and which may be readily connected in circuit. Another object of my invention is to provide a structure which shall reduce heating and skin effect to a low value and insure a good electrical connection between the clip-block terminal and the bus bar or other conductor to which the switch is connected.

In an electric conducting system where a single lap joint connection is used, conductors carrying heavy currents have to be relatively thick in order to provide sufficient conducting capacity and it becomes difficult to avoid undue heating. Those versed in the art, therefore, prefer to have the thickness of the conductor bars or connectors not over one-fourth of an inch as by so doing the amount of heating is minimized. Although in high ampere capacity lever switches having milled slots in the block extensions for use in bolting on connections, a multiple lap joint or laminated terminal of substantially thin members in a part of the structure may be obtained, the milled slots are ordinarily rough and cannot readily or economically be made smooth. Furthermore the milled block makes a more inflexible structure which it is difficult properly to bolt to a uniform bearing surface. Consequently, the connection does not permit a uniform current density and its conductivity is also reduced.

According to my invention, I provide a combined or unitary clip-block and terminal, hereinafter referred to as a clip-block, of mechanically substantial construction which may be easily and efficiently connected to an electric conducting system by means of its

laminated terminal of substantially thin bars, which because of the flexibility of its laminated structure provides a substantially uniform and low current density per unit area of bolted contact surface, which has a large radiating surface per unit volume of conductor, and in which eddy current losses and skin effect are reduced to a minimum, all of which act to keep heat losses at a minimum and at the same time provide a maximum heat dispersing effect.

My invention will be better understood from the following description taken in connection with the accompanying sheet of drawings, and its scope will be pointed out in the appended claims.

Figure 1 illustrates my invention embodied in an electric conducting system including a lever switch; Fig. 2 shows an embodiment of my invention in perspective; Fig. 3 is a section on the line III—III of Fig. 2; Fig. 4 shows in perspective the embodiment of my invention shown in Fig. 2, the parts being shown disassembled; Fig. 5 is a sectional view illustrating a modification of my invention; and Fig. 6 is an elevation illustrating a modification of my invention.

Fig. 1 illustrates an application of my invention embodied in an electric conducting system, including conductors 1 arranged to be connected in circuit by an electric switch 2 mounted on a suitable base 3 of insulating material which may be a switchboard panel or the like. The switch 2 is provided with hinge and contact clip-blocks 4 and 5 respectively, embodying my invention, the laminated extensions or terminals 6 of the clip-blocks having the conductors 1 secured thereto by any suitable means such as bolts 7. The clip-blocks 4 and 5 may be secured to the insulating base 3 by any suitable means such as screws 8, the clip-blocks being suitably spaced apart and the lever or blade 2 of the switch, which is hinged for movement in the hinge clip-block 4, engaging the contact clip-block 5 in the closed position.

The embodiment of my invention illustrated in Figs. 2, 3 and 4 comprises a plurality of standard size flat bars 6 of good conducting material, for example, copper, having the necessary length and preferably not over one-fourth of an inch thick, the num-

ber of bars required depending upon the current to be carried. Where a clip-block is to be mounted on an insulating base as shown in Fig. 1, the bars 6 are bent intermediate their ends preferably in a power press so that the end portions are in substantially parallel offset planes. This provides for the necessary clearance between the base and the terminal 6 of the clip-block for bolting the connection as shown in Fig. 1. When this clearance is not needed the bars 6 are left straight. The bars 6 are then stacked alternately with spacer bars 9 preferably of the same thickness and between every two adjacent bars 6 at one end thereof and clamped together. Countersunk holes 10 for rivets 11 and screw or bolt holes 12 and 13 for fastening the clip-block to the insulating base and to the connector respectively are drilled. The rivets 11 are then placed in the holes 10 and upset thus holding the bars together.

The assembled stack of bars is now slotted preferably in a milling machine, the slots 14 being cut to receive the switch clips 15. These clips, which may have cuts 16 to provide a more resilient and uniformly contacting structure for the circuit closing member of the switch, are then inserted in the slots 14. Holes 17 are now drilled in one of the bars 6 or 9, preferably an intermediate bar, transversely of the slots 14 and through the inserted portions of the clips 15 and pins 18 inserted in the holes 17. The structure thus assembled is placed on a hot plate with the lower bar in contact with the plate as by so doing the heat is concentrated at the riveted ends of the bars where it is wanted and furthermore has substantially no effect on the inherent or natural resiliency of either the clips or the spread terminal of the block. When the metal has reached the necessary temperature, the meeting surfaces of the bars 6 and 9 and of the bars 6 and 9 and the clips 15 are sweated together in a manner well known to the art thus forming a compact unitary structure. For a contact clip-block such as shown in Fig. 2, it is sometimes desirable to provide blade stops 19; see Fig. 3. These are mounted in recesses 20 cut in one or more of the upper bars 6 and 9 and sweated therein when the clips and bars are sweated together.

Fig. 5 illustrates a modification of my invention, the block being shown in section on the center line of the bolt holes for securing the clip-block to the base, that is, a section similar to Fig. 3. The clip-block shown in Fig. 5 is a hinge clip-block having holes 21 for the hinge pin or bolt of a switch blade. In this modification of my invention all of the bars 6 and 9 are not slotted for the clips 15 which may abut any one of the lower bars such as 9, and are thus readily brought to

alignment at the upper ends. Obviously it is preferable to have the pin holes 17, see Figs. 2 and 3, in an intermediate bar.

Fig. 6 shows a clip-block embodying a modification of my invention comprising a plurality of bars 6 and clips 15 bent and assembled as heretofore described but without the spacer bars 9. This modification of my invention is obviously adapted to carry heavy currents and as no spacer bars 9 are used the amount of material to be slotted is reduced as compared with the clip-block shown in Figs. 2 and 4 when constructed for equivalent ampere capacity.

Referring to Figs. 1, 2 and 6, it is obvious that the free air space 22 between the surfaces of the bars 6 forming the laminated or spread terminal increases the additional radiating surface obtained by the use of the laminated terminal so that a maximum of radiating surface for a given ampere capacity is provided. It is also obvious that clip-blocks constructed in accordance with my invention although forming a compact unitary structure have a terminal of flexible laminations which provide for a bolted connection giving substantially uniform pressure between smooth surfaces and therefore substantially uniform current density and maximum current carrying capacity.

What I claim as new and desire to secure by Letters Patent of the United States, is,—

1. The method of making a clip-block for electric switches comprising a plurality of flat bars and switch clips which consists in bending a plurality of said bars intermediate the ends thereof so that the end portions are in substantially parallel offset planes, riveting said flat bars together at one end, forming slots in the riveted end of one of said flat bars, inserting clips in the slots thus formed, drilling holes transversely of said slots in one of said bars and through the inserted portions of said clips, inserting pins in said holes, and sweating together the meeting surfaces of said bars and of said bars and said clips whereby a unitary clip-block having a spread terminal is formed.

2. A clip-block for electric switches comprising a plurality of flat conductor bars fastened together at one end and having their free ends spaced apart to form a laminated terminal, one of said bars having slots in its fastened end, and clips inserted in said slots and secured therein by pins through holes transversely of said slots in said slotted bar and the inserted portion of each of said clips.

3. A clip-block for electric switches comprising a laminated structure including a plurality of flat bars fastened together and slotted at one end, and clips inserted in the slotted portion of said laminated structure

and secured therein, said bars being spread apart beyond the clips to provide a terminal having separated laminations.

4. A clip-block for electric switches comprising a plurality of flat bars fastened together at one end, and clips inserted and secured in slots in said end, said bars and said clips being sweated together to form a unitary structure and said bars being

10 spread apart beyond said clips to form a laminated terminal.

5. A clip-block for electric switches comprising a plurality of flat bars having their end portions in substantially parallel offset planes, said bars being fastened together and slotted at one end, and clips inserted and secured in the slots of said end, the meeting surfaces of said bars and of said

bars and said clips being sweated together to form a unitary structure.

20

6. A clip-block for electric switches comprising a laminated structure including a plurality of flat bars bent intermediate their ends so that the end portions are in substantially parallel offset planes and an intermediate flat bar, said bent bars being fastened together at one end with said intermediate bar between two adjacent bent bars, and clips secured in slots in the laminated structure thus formed, said clips and said

25

30

bars being sweated together to form a unitary structure.

In witness whereof, I have hereunto set my hand.

WAYNE E. WEDEMAN.
